BOTTOM HOLE CHOKE

Ernest L. Barker and Charles P. Gillespie,
Houston, Tex.

Application March 14, 1939, Serial No. 261,732

15 Claims. (Cl. 166—2)

This invention relates to well chokes, and has particular reference to that type of well choke customarily referred to as bottom hole choke.

The general object of this invention is to provide a bottom hole choke which may be placed in and removed from a well whenever desired without necessity for removing the well tubing.

It is to be understood that the term "bottom hole choke" wherever used in this application is to be taken as meaning any choke which is adapted to be located in a well below the upper end thereof. It is not intended to be limited to a choke located at the extreme bottom end of the well.

Under certain circumstances it has been found desirable to place well chokes at a point down in the well usually near the bottom thereof, rather than to place the choke in the Christmas tree at the top of the well as is perhaps the most common practice. Modern wells, however, are drilled frequently to greater depths, sometimes approaching three miles below the surface of the earth and it is not at all inconceivable that wells in the not distant future will exceed three miles in depth. The expense and time involved in removing and inserting a tubing of such great length is such that it would be prohibitive to permanently position a choke in the bottom of a tubing of a well of such great depth because this would necessitate the removal and replacement of the entire tubing whenever the choke happened to wear out due to abrasion or become otherwise damaged or plugged. Furthermore, although various attempts have been made in the past to provide chokes which may be dropped or lowered into the tubing to seat adjacent the bottom thereof and to be removed therefrom by means of a cable or the like when desired, these have proven objectionable because in many instances they cannot even be made to move downwardly in the well. The choke assembly is necessarily of a size to substantially fill the tubing and the choke opening is so small that if the well is such as to produce a great volume, the flow from the well may be greater than will move past and through the choke assembly. In such instance, naturally, the device will be carried upwardly by the flow and not permitted to move downwardly into the well. Even if there be no flow as for example if the well is completely closed down during the time the device is being lowered into the well, substantially the entire amount of fluid in the well must pass through the relatively small choke opening as the device passes downward toward the bottom of the well. This makes the assembly

move very slowly indeed and in the case of wells of great depth such as hereinbefore referred to necessitates a long period of shut-down.

It is one of the objects of this invention to provide a choke which may be quickly lowered into place within a well through the well tubing or other flow pipe in the well, and without any connection with the upper end of the well.

Another object is to provide a means for retrieving such a choke assembly, which means will ordinarily not require the use of a cable or the like and will not require the removal of the well tubing.

Another object of this invention is to provide a choke which may be placed in or removed from a well without necessity for removing the well tubing and without necessity for shutting down the well for any considerable period of time.

Other objects and advantages will appear more fully from the following description taken in connection with the accompanying drawing, wherein is set forth one embodiment of this invention by way of illustration and example.

In the drawing:

Fig. 1 is a longitudinal cross section through a choke assembly constructed in accordance with this invention, as the same appears when it is about to be lowered into a well.

Fig. 2 is a similar view showing the same device after it has been positioned at the desired point within a well tubing.

Fig. 3 is a view similar to Fig. 2 but on a reduced scale and illustrating the means and manner of withdrawing or retrieving the choke assembly.

Fig. 4 is a transverse cross section taken along the line 4—4 of Fig. 3.

Fig. 5 is a transverse cross section taken along the line 5—5 of Fig. 1.

Fig. 6 is a transverse cross section taken along the line 6—6 of Fig. 1.

Fig. 7 is a transverse cross section taken along the line 7—7 of Fig. 1.

In accordance with this invention, the choke 1 which consists simply of a tubular member with an opening therethrough of the size which is desired for the choke, is carried by a member 2 forming part of a choke holder. The choke 1 is preferably of very hard material which will resist abrasive and other deteriorating influences existing in an oil or gas well. The member 2 is formed with an enlarged portion or chamber adjacent its upper end and with a restricted portion 2a adjacent its lower end. This restricted portion 2a fits fairly snugly about the choke 1.

Surrounding the choke 1 and passing through the part 2a is a plurality of openings 2b which serve to by-pass the choke under certain circumstances as will be presently set forth. The choke is, at the time while it is being lowered into a well, held in the position illustrated in Fig. 1 by means of screws 3 threaded into the member 2 and having shear portions projecting into openings in the side walls of the choke member 1. When in this position, the lower end portion 4 of the choke member projects below the member 2 and the upper enlarged end 5 of the choke member is located within the enlarged upper portion of the member 2 which was previously referred to. The outer surface of this enlarged upper end of the choke is formed with a conical seat 6 adapted when the choke member is moved upwardly within the member 2 to seat within a conical portion 7 in a second fitting 8. The taper of the surfaces 6 and 7 is such that when these parts are forced together they will stick and the choke 1 will not thereafter drop away from the member 8.

The member 8 is threaded into the upper end of the member 2 and has a portion immediately above the member 2 which is of smaller outer diameter than the member 2. At the upper end of this portion is a shoulder 9 and above this shoulder the member 8 is of the same diameter as the member 2. Between the shoulder 9 and the upper end of the member 2 and surrounding the portion 8 of reduced diameter there is a plurality of sealing cups 10 spaced apart by space rings 11 and turned downwardly so as to expand and form a seal with respect to a well tubing to prevent flow upwardly about the outer portion of the choke holder within which the choke 1 is mounted.

The upper end of the fitting 8 is provided with a portion 12 of enlarged internal diameter and within this portion is carried a part 13 which might be termed a bushing. This part 13 is bifurcated, and pivoted between the parts thereof at 14 there are levers 15. The upper ends of these levers are of circular or cylindrical form 16 adapted to fit within correspondingly shaped sockets 17 formed in each of a pair of radially movable latching members 18. Each of these latching members has a latching part or bolt which is beveled on its lower outer corner as at 19 and provided with a sharp shoulder at its upper outer corner as shown at 20. Bearing against the lower ends of the levers 15 and tending to hold them always in a position to move the latching members 18 outwardly, are springs 15a. The lower ends of these levers when the latching members 18 are at their outermost position will lie closely adjacent to each other and will project inwardly beyond the inner contour of the split bushing 13. The latching members 18 are at their inner ends cut away as shown at 21 so that when moved to their innermost position they will still leave an opening as great in diameter as the inner diameter of the bushing 13.

The latching members 18 are carried by a fitting 22 which is secured to the upper end of the member 8 by means of welding 23 or the like. This fitting 22 is preferably integral or integrally joined to the upper end of the split bushing 13. This fitting 22 is provided with a portion of reduced external diameter at its upper end, this portion being externally threaded as at 24. The fitting is also provided with a longitudinal passageway 25 of the same diameter as the split bushing 13, and this passageway terminates at

its upper end with a flared portion 26 so as to guide any member entering the same from above into the passage 25.

Threadedly connected to the fitting 22 by means of threads 24 is a retrieving fitting 27 having annular channels 28 therein for a purpose presently to be set forth. The upper end of this fitting 27 is likewise flared at 29 so as to guide a member from above into the interior of this fitting.

In operation, the device just described is assembled in the form shown in Fig. 1 and is inserted free into the upper end of a well tubing 30, down which it travels by gravity. The latching members 18 will be held inwardly by the walls of the tubing 30 and will be permitted to pass by couplings and other obstructions in the tubing by virtue of the inclined lower outer corners 19. The sealing cups 10 will prevent any flow upwardly around the outside of the assembly but flow may take place not only through the interior of the choke 1 but around the outside of this choke through the by-pass openings 2b. Flow through these openings may pass upwardly through the enlarged interior portion of the member 2 and around the head 5 of the choke, thence upwardly through the member 8, the fitting 22 and the fitting 27, all forming parts of the choke holder. It will thus be seen that substantially free flow will be permitted upwardly past the choke through the assembly while the same is being lowered into the well. At a point adjacent the lower end of the well or wherever it is desired that the choke be positioned, there is inserted in the tubing by any appropriate means a spider 31 which forms an abutment for the lower end 4 of the choke. This spider 31 in the present instance, as shown in Fig. 2, is located within a collar 32 and between the two adjacent ends of the tubing threaded in said collar. The spider serves as an abutment as above stated but has openings 33 therethrough so as to permit substantially free flow of fluid from the well. Due to the fact that fluid is permitted to by-pass through the passage 2b and is not all forced to flow through the choke 1 which is of relatively small diameter, the assembly will move quickly to its position within the well and no great amount of time will be required such as would be required if the entire amount of fluid in the well were forced to flow through the choke opening.

When the choke assembly reaches the position where it is to be located in the well, the lower end 4 of the choke will strike the spider 31 causing the shearing of the ends of the screws 3 and the movement of the choke upwardly with respect to the fitting 2. This moves the head 5 upwardly into the lower end of the fitting 8 and causes the conical surface 6 to seat within the portion 7 of the fitting 8. The action just described will prevent any further passage of fluid through the openings 2b. The only flow which can now take place from the well past the assembly which has been described is that flow which can take place through the choke 1. Inasmuch as the well would force a greater potential output than could pass through the choke 1 or else the choke would not be needed, pressure will build up underneath the assembly and will tend to move it upwardly in the tubing. This upward movement will take place until the latches 18 arrive at the next coupling 34 above the point where the abutment 31 is reached. When the latches 18 reach the coupling 34 they will be urged outwardly by the springs 15a and will latch

at this coupling as indicated in Fig. 2. The well will now continue to flow through the choke 1 but no other flow can take place. The assembly comprising the fittings 2, 8, 22 and 21 constitute a means for holding this choke and for preventing any passage of fluid around the choke. The sealing cups 10 form a seal about the outside of the choke holder while the choke itself seats against the portion 1 to prevent the by-passing of fluid through the openings 2b.

In the event the choke becomes worn so that too great an amount of fluid is allowed to flow from the well, or in the event it becomes otherwise damaged or plugged with some foreign matter, provision is made for the withdrawal or retrieving of the choke assembly.

For the purpose of thus withdrawing the choke assembly, there is provided a device comprising a weighted body 35 having grooves 36 in its outer surface and having a downwardly projecting portion 37 of slightly smaller diameter than the inner diameter of the fitting 21. The weight 35 is preferably of a diameter only slightly smaller than the inner diameter of the tubing so that it will serve as a guide for the device while the grooves 36 will serve to permit free passage of fluid past the weight as it is lowered into the well. Surrounding the portion 37 which is adapted to enter the fitting 21 there is provided a plurality of sealing rings 38 adapted to contract as they pass into the fitting 21 and to expand within this fitting into the grooves or channels 28. These will serve to substantially shut off all flow through the choke assembly, whether through the choke proper or otherwise.

At the same time, there is a projection 39 of smaller diameter than the part 37 and of a diameter only slightly smaller than the passageway 25. This projection will pass downwardly through the passage way 25 between the latching members 18 and between the levers 15. This part is pointed or tapered on its lower end as shown at 40 so that as it passes between the lower ends of the levers 15 it will force these lower ends away from each other and draw the latching members 18 inwardly out of latching position. This is clearly shown in Fig. 3 of the drawing. The members 18 can move inwardly to unlatched position when the member 39 is between them because of the previously described cutaway parts 21 on the inner ends of these latching members.

It will now be seen that the choke assembly has been plugged so that substantially no flow can take place from the well past the assembly or through it, and it has been unlatched by the withdrawal of the latching members 18. It will now act as a piston within the tubing 30 and will be forced upwardly by the pressure within the well until it is forced entirely out of the well. In the event the assembly should be caught on some projection or if for some other reason it should not be forced out of the well by the well pressure, it may be retrieved by means of an ordinary overshot or a cable, which overshot may be lowered into latching engagement with the spear head 41 on the upper end of the weight 35.

It will be seen from the foregoing that a means has been provided whereby a choke may be positioned within a well tubing and removed therefrom without necessity for removing the tubing from the well and without necessity for shutting down the well for any considerable period of time. It will further be seen that a means has

been provided whereby a choke may be lowered rapidly into a well and removed rapidly therefrom.

All of the objects and advantages sought by this invention can, it will be appreciated, be accomplished by the structure set forth.

Having described our invention, we claim:

1. In combination with a choke adapted to be lowered into a well to control flow at a point below the upper end thereof, a choke holder, means on said choke holder for preventing upflow from said well about said choke holder, said choke holder having a passageway for by-passing fluid past said choke through the interior of said holder while said choke and choke holder are being lowered into a well, means for closing said by-pass passageway when said choke reaches a predetermined point in the well, and means for latching said choke holder against upward movement from the well.
2. In a bottom hole choke assembly, a choke, a hollow choke holder for holding said choke and having means for by-passing fluid through itself around said choke while the assembly is being lowered into a well, means for closing said by-passing means when said choke reaches a predetermined point in the well, means for preventing upflow about any portion of said choke holder, and means for latching said choke holder against upward movement from a well.
3. In combination a choke assembly comprising, a choke, a choke holder for holding said choke and having fluid by-pass means for by-passing fluid around said choke while the assembly is being lowered into a well, means for preventing upflow about said choke after it has reached a predetermined point in a well, means for latching said assembly against upward movement from a well, and means for releasing said latching means and shutting off flow through said choke when it is desired to remove said choke assembly.
4. In combination, a choke, a choke holder having a part of its length provided with a by-pass means for conducting fluid around said choke, and part of its length adapted to form a seal about said choke, means for releasably holding said choke in said first part of the choke holder during the lowering of said choke and choke holder into a well, and means for causing said choke to move into said other part and close off said by-pass means when said choke and choke holder reach a predetermined point in a well.
5. In combination, a choke, a choke holder having a part of its length provided with by-pass means for conducting fluid around said choke, and part of its length adapted to form a seal about said choke, means for releasably holding said choke in said first part of the choke holder during the lowering thereof into a well, means for causing said choke to move into said other part and close off said by-pass means when said choke and choke holder have reached a predetermined point in a well, and means carried by said choke holder for latching the same against upward movement in a well.
6. In combination, a choke, a choke holder having a part of its length provided with by-pass means for by-passing fluid around said choke and part of its length adapted to form a seal about said choke, means for releasably holding said choke in said first part of the choke holder during the lowering thereof into a well, means for causing said choke to move into said

other part and close off said by-pass means when said choke and choke holder have reached a predetermined point in a well, free floating means for latching said choke holder against upward movement from a well, and means for releasing said latching means and stopping flow through said choke and choke holder when it is desired to remove said choke from the well.

7. In combination, a choke, a choke holder having a lower part provided with by-pass means for by-passing fluid around said choke and a higher part adapted to form a seal about said choke, means for releasably holding said choke in said lower part of the choke holder during the lowering thereof into a well, and means for causing said choke to move into said higher part and close off said by-pass means when said choke and choke holder have reached a predetermined point in the well.

8. In combination, a choke, a choke holder having a lower part provided with fluid by-pass means for by-passing said choke and an upper part adapted to form a seal about said choke, frangible means for releasably holding said choke in said lower part of the choke holder during the lowering thereof into a well, and means for causing said choke to move upwardly into said upper part of the choke holder to close off said by-pass means when said choke and choke holder have reached a predetermined point in the well.

9. In a device for retrieving a bottom hole choke assembly held by a latch, a body member having a latch releasing part adapted to release said assembly for upward movement in a well, and a part carried by said body member adapted to substantially close said assembly against upflow therethrough, whereby pressure may accumulate below the same.

10. In a device for retrieving a bottom hole choke assembly, a heavy weighted body having parts adapted to guide the same in its passage through a tubing, said body having parts providing for the passage of fluid past the same, a latch releasing part on said body adapted to release said assembly for upward movement in a well, and a part on said body adapted to substantially close said assembly against upflow therethrough.

11. In a device for retrieving a bottom hole choke assembly, a heavy weighted body having parts adapted to guide the same in its passage through a tubing, said body having parts providing for the passage of fluid past the same, a latch releasing part on said body adapted to release said assembly for upward movement in a well, a part on said body adapted to substantially close said assembly against upflow therethrough, and means on the upper end of said body adapted to be engaged by a retrieving tool

whereby said body may be forcibly pulled from a well.

12. In combination, a choke, a choke holder in which said choke is movably mounted, said holder having fluid by-pass means for by-passing fluid around said choke, means for releasably holding said choke in a position permitting flow through said by-passing means while the assembly is being lowered into a well, and means operable when said assembly reaches a predetermined point in the well for shifting said choke to another position in which it prevents up flow through said by-passing means.

13. In combination, a choke, a choke holder in which said choke is movably mounted, said holder having fluid by-pass means for by-passing fluid around said choke, means for releasably holding said choke in a position with its end projecting below said holder while the assembly is being lowered into a well, in which position it permits free flow through said by-passing means, and means engageable with the end of said choke when said assembly reaches a predetermined point in the well for shifting said choke to another position in which it prevents up flow through said by-passing means.

14. In combination, a choke, a choke holder for holding said choke and having fluid by-pass means for by-passing fluid around said choke while the assembly is being lowered into a well, means operable when said choke reaches a predetermined point in a well for preventing up flow about said choke thereafter, means movable radially through said holder and relatively fixed longitudinally thereof for latching said assembly against upward movement from a well, and means separate from but insertable in said holder for releasing said latching means when it is desired to remove said choke assembly from the well.

15. In combination, a choke, a choke holder having a part of its length provided with by-pass means for conducting fluid around said choke and part of its length adapted to form a seal about said choke, means for releasably holding said choke in said first part of the choke holder during the lowering thereof into a well, means for causing said choke to move into said other part and close off said by-pass means when said choke and choke holder have reached a predetermined point in a well, means for latching said choke holder against upward movement from a well, and free floating means adapted to be dropped into the well for releasing said latching means when it is desired to remove said choke from a well.

ERNEST L. BARKER.
